W. J. SMITH.
FLUME OR CONDUIT.
APPLICATION FILED MAR. 23, 1911.

Patented Mar. 11, 1913.

UNITED STATES PATENT OFFICE.

WILLIAM JOHN SMITH, OF SAN LUIS OBISPO, CALIFORNIA.

FLUME OR CONDUIT.

1,055,426.

Specification of Letters Patent. Patented Mar. 11, 1913.

Application filed March 23, 1911. Serial No. 616,546.

To all whom it may concern:

Be it known that I, WILLIAM J. SMITH, residing at San Luis Obispo, in the county of San Luis Obispo and State of California, 5 have invented a new and Improved Flume or Conduit, of which the following is a specification.

My present invention relates to water carrying troughs or flumes for irrigating 10 or other ditches, and more particularly to that type of trough or flume structure disclosed in my Patent No. 971,087 granted September 27, 1910, and my present invention seeks to provide certain improvements 15 on my patented flume structure that simplifies and reduces the cost of putting up the said structure.

My invention consists in certain details of construction and novel arrangement of 20 parts, all of which will hereinafter be fully explained, specifically pointed out in the appended claims and illustrated in the accompanying drawings, in which:—

Figure 1, is a perspective view of my 25 present invention. Fig. 2, is a cross section of the same on the line 2—2 on Fig. 1. Fig. 3, is a detail longitudinal section thereof. Fig. 4, is a longitudinal section on the line 4—4 on Fig. 2. Fig. 5, is a perspective 30 view showing the various parts separated.

In the present construction of my invention, the side rails of the flume are arranged and mounted in the usual manner. The flume sections 2—2, in the present case, are 35 trough-shaped and preferably semi-circular in cross section. Each of the sections 2 has a pair of closely related and parallel transverse grooves 21—21 at one end thereof that extend the full width of the sections and 40 which form pockets for receiving the packing members 3—3 of such material that compresses tightly down into the grooves when the overlapping smooth end of the adjacent section is clamped down upon the 45 same, the said packing 3 in my present case being also preferably of cylindrical shape in cross section, so when placed in the grooves 21, the upper part thereof protrudes to produce yielding bearings for the smooth ends 50 of the upper sections 2 and thereby form positive water-tight joints where the several parts are clamped together.

4 designates flat bands that pass under the metal trough sections 2 and engage 55 them, preferably at a point between the pendent beads or flanges 21^a—21^a formed

by the grooved portions 21. The bands 4 in my present case serve as the main supports for the flume or trough body and they have their opposite ends turned at an angle 60 to form flanges 40—40 for resting upon the side sills 1—1, as clearly shown in Fig. 2 of the drawings. By fitting the bands 4 between the flanges 21^a—21^a the said bands also retard undue longitudinal expansion of 65 the flue sections and further by reason thereof also relieve the fastening means that secures the flanges of the bands 4 to the side sills from undue strain.

In my present case, I use but one set of 70 bolts 5—5 for fastening the flanges of the bands 4 and these bands pass down through the side sills 1 and are secured by the nuts 7, as shown, and to provide against the bolt head wearing loose and also to provide for 75 a positive seating of the sections 2 onto the bands 4, web-like washers 23 are provided, and these are mounted over the flanged ends of the supports 4, as clearly shown in Fig. 2.

By reason of constructing the invention 80 in the manner shown and described, considerable saving of expense in the trough sections 2 is avoided as the side flanges thereof are not required as the entire weight of the side sections is carried by the bands 4. 85

From the foregoing taken in connection 90 with the accompanying drawings, the advantages of my construction of flume will be readily apparent.

What I claim is:

1. In a flume or conduit of the character described, the combination with opposite side rails; of a plurality of metallic sections whose adjacent ends overlap, the upper end of each section having a pair of parallel 95 transverse grooves on the inner face and like pendent flanges on the outer face, a compressible packing in each of the said grooves, a strap band that engages the metallic sections at a point between the pendent flanges and 100 whose ends are supported on the opposite side rails, and means for clamping the overlapping portions of the metallic sections and the said band and securing them on the said rails. 105

2. The combination with the opposite side sills; of a plurality of sheet metal sections of semi-circular shape, the adjacent ends of each pair of sections overlapping, the upper end of each section having a pair of pendent 110 transverse flanges, a packing strip held between the sections and extending the full

- transverse width thereof, the flanges of the said sections being mounted on the side sills, a strap band that forms a hanger of semi-circular shape that engages the metal sections at a point between the pendent flanges thereof, the ends of the said band hanger resting on the side sills, and fastening bolts that pass through the rest portions of the band hangers and through the side sills.
5. The combination with the side sills, of the metallic trough sections, each section having a plurality of depressed portions extending the full width thereof, the said depressed portions forming pockets on the inner face, and pendent beads or flanges on the outer faces of the sections, a strap metal band hanger that engages the under side of the trough sections between the pendent flanges thereof, the said strap hangers having apertured end portions for resting on the side sills, a bolt that passes through the rest ends of the strap hanger and the side sills, and a clip washer between the head of the bolt and the side flanges of the metallic sections.
10. 3. The combination with the side sills, of the metallic trough sections, each section having a plurality of depressed portions extending the full width thereof, the said depressed portions forming pockets on the inner face, and pendent beads or flanges on the outer faces of the sections, a strap metal band hanger that engages the under side of the trough sections between the pendent flanges thereof, the said strap hangers having apertured end portions for resting on the side sills, a bolt that passes through the rest ends of the strap hanger and the side sills, and a clip washer between the head of the bolt and the side flanges of the metallic sections.
15. 4. A flume or trough formed of sections having overlapping ends, at least one of such ends of a section being provided with a pair of transverse beads, a flat clamping bar disposed between said beads, and edge clamping members coöoperating with said bar to clamp said overlapping ends together.
20. 5. A flume or trough formed of sections

having overlapping ends, at least one of such ends being provided with a pair of transverse beads spaced apart, a flat clamping bar disposed between said beads and extending from one side edge of the flume to the other, and means for securing said bar and said overlapping ends together to hold 40 said overlapping ends in position.

6. A flume or trough formed of sections having overlapping ends, supporting members at each side of said flume, at least one of said overlapping ends being provided 45 with a pair of transverse beads spaced apart, a flat clamping bar extending under said overlapping ends adjacent to said beads, and having bent over ends to engage said side supports, means coöperative with said bar 50 for clamping said overlapping ends together and securing said trough to said side supports.

7. A flume or trough formed of sections having overlapping ends, at least one of 55 said ends having transverse beads, means for clamping said sections between said beads, said means including a flat clamping bar disposed between said beads, and co-operative clamping members coöperating 60 with said bar to secure said overlapping ends together.

WILLIAM JOHN SMITH.
